UNITED STATES PATENT OFFICE

ABRAHAM M. HERBSMAN, OF HUNTINGTON PARK, AND RODNEY B. CAMPBELL, OF WALNUT PARK, CALIFORNIA; SAID CAMPBELL ASSIGNOR TO SAID HERBSMAN

DESIGN FOR A HAND SPRAY DEVICE

Application filed November 11, 1932. Serial No. 45,886. Term of patent 14 years.

To all whom it may concern:

Be it known that we, ABRAHAM M. HERBSMAN, a citizen of the United States, residing at Huntington Park, in the county of Los Angeles, State of California, and RODNEY B. CAMPBELL, a citizen of the United States, residing at Walnut Park, in the county of Los Angeles, State of California, have invented a new, original, and ornamental Design for a Hand Spray Device, of which the following is a specification, reference being had to the accompanying drawing, forming part thereof.

Fig. 1 is a side elevational view of the article showing our new design.

Fig. 2 is a rear elevational view thereof.

Fig. 3 is a plan view thereof.

We claim:

The ornamental design for a hand spray device as shown.

In testimony whereof, we have hereunto set our hands at Los Angeles, California, this 18th day of October, 1932.

ABRAHAM M. HERBSMAN.
RODNEY B. CAMPBELL.
